Attorney.

UNITED STATES PATENT OFFICE

ROBERT J. DOUGHERTY, OF AMBLER, PENNSYLVANIA, ASSIGNOR TO JOHN WOOD MANUFACTURING COMPANY, OF CONSHOHOCKEN, PENNSYLVANIA, A CORPORATION OF PENNSYLVANIA

ELECTRICAL CONTROLLING SYSTEM FOR GAS WATER HEATERS

Application filed November 14, 1931. Serial No. 575,042.

My invention relates to apparatus of the general class contemplated in Letters Patent of the United States 1,715,040 granted to Victor Mauck May 28, 1929, for domestic heating, wherein the water heated is forcibly circulated through a piping system including radiators remote from the heater, and conveniently by an electrically actuated pump, and the operation of the heater is automatically controlled by thermostatic means operative upon a valve to supply more or less fuel gas to the burner in accordance with the temperature of the atmosphere surrounding the thermostat. That is to say, when said atmosphere reaches a predetermined temperature, the supply of gas to the burner is diminished to such a degree that only a small pilot flame is maintained, but such flame is enlarged by automatically opening the gas valve, by electrically controlled means, when the temperature at the thermostat falls below a predetermined degree. Such thermostatic controlling means is also operative upon the motor which actuates the water circulating pump. Moreover, said pilot flame is in cooperative relation with a thermostatically controlled switch; so that if and when said flame is accidentally extinguished, the flow of gas through the pilot burner is automatically stopped, to not only prevent waste of gas thereat but eliminate the possibility of ultimate explosion of gas flowing from the burner unignited.

Such apparatus conveniently includes heater sections of a cellular type, formed of congeries of thin copper flue tubes having their opposite ends enlarged and connected, laterally, by solder, to form water spaces around the tubes. Such heater units are extremely efficient in the transfer of heat from the flue gases to the water, but it is necessary to avoid raising the temperature of such cellular structure to such a degree that the water pressure would disrupt the soldered joints. Therefore, such apparatus includes means automatically insuring that the water shall be actively circulating in the heater sections, each time the heating effect of the burner is augmented in response to the operation of said thermostat to produce more heat, to thus

prevent overheating the soldered joints by the increased consumption of gas. Such means includes an electrically operated and controlled water pump, whereby the water is forcibly circulated in the heater system at such a rate as to absorb substantially all of the heat from the products of combustion. Although that effect is desirable for efficiency of combustion of the fuel, it leaves the products of combustion at such low temperature that the mere convection force thereof is sometimes insufficient to alone discharge the products of combustion through a flue to a chimney or other discharge outlet. Therefore, said apparatus preferably includes an electrically operative and controlled fan in said flue, for supplementing the convection force of the products of combustion to effectively discharge them from the heater.

Ordinarily, such apparatus is electrically controlled by a complicated system wherein both high and low voltages are employed in cooperative relation; for instance, a portion of the circuit may be energized at 110 volts and another portion at 20 volts. Such a construction and arrangement not only necessitates the employment of a transformer to generate the low voltage energy from the high voltage energy, but is more difficult and, consequently, costly to wire and requires a person highly skilled in the art to not only initially connect it but to make any subsequent repairs and avoid destruction of parts of the apparatus included in the low voltage circuit by accidental connection with the high voltage circuit. Therefore, an object and effect of my present invention is to provide for such a heater as above described a much simpler electrical controlling system which may be energized entirely from an ordinary 110 volt house lighting circuit; eliminating the delicate and costly controlling elements which have heretofore been required to be energized by the low voltage circuit.

My invention includes the various novel features of construction and arrangement hereinafter more definitely specified.

In said drawings; Fig. I is a vertical sectional view of such a heater casing taken on the line I, I, in Fig. II, showing the other

elements of the heater in elevation, as seen from the front.

Fig. II is a vertical sectional view of the heater casing taken on the line II, II, in Fig. I and showing some of the interior elements of the heater in elevation, as seen from the right hand side of Fig. I.

Fig. III is a wiring diagram showing the connection and cooperative relation of the various elements of the heater with a preferred embodiment of my improved electrical controlling system.

In said figures; the outer casing 1 of the heater, which is conveniently formed of sheet metal, is rectangular in plan with its walls connected by corner angle bars 2. The cylindrical heat insulating jacket 3 is mounted with its axis vertical in one corner of said outer casing 1 surrounding the cylindrical tubular water jacket 4 inclosing the combustion chamber 5. Water is supplied to said heater through the pipe 7 and rotary pump 8, and conduit 9 leading to said jacket 4. As shown in Fig. II, said pump 8 is directly connected with the armature shaft 10 of the electric motor 11.

As shown in Fig. II, said water jacket 4 is connected by the conduit 13 with the heater unit section 14 which is connected by the coupling 15 with the similar heater unit section 17 from which the hot water discharge conduit 18 leads to suitable radiators.

The main gas burner 20 is mounted in said combustion chamber 5 and supplied with gas from the pipe 21 through the conduit 22 under control of the valve 23 in the casing 24 arranged to be opened by the electric motor 25 and closed by the spring 26. The device indicated at 27 in Fig. I is a regulator of the diaphragm type which renders the pressure of the gas supplied to said burner 20 substantially uniform, regardless of fluctuations in pressure of the gas supplied to the heater.

I find it preferable to retard the flow of products of combustion through the heater by directing them through the baffle ring 28 against the baffle plate 29. Said products pass around said baffle plate 29, and through a series of small open copper tubes extending vertically in said heater sections 14 and 17. Said tubes have hexagonal enlargements at their opposite ends, which are soldered together. The water circulates around said tubes through the interstices between them and absorbs the heat from the products of combustion which pass through said tubes into the horizontally extending flue casing 30, which has the flue outlet flange 31 engaging the flue pipe 32.

I find it convenient to create a forced draft of the products of combustion from said chamber 5, through said flue flange 31, by means of the rotary fan 34 which is mounted on the armature shaft 35 of the electric motor 36. Said flue casing 30 is spaced from

the jacket 3 by the insulating jacket 38 surrounding said heater sections 14 and 17, and is rigidly connected with said jacket 4, conveniently by the bolts 39 and nuts 40 shown in Fig. I; said nuts being accessible through the hand hole 41 in said casing 30 which is normally closed by the cover 42.

The pilot burner 45 is supplied with gas through the conduit 46, from the pressure side of the valve 23 so that, under normal circumstances, a flame 47 is maintained at said pilot burner in position to ignite the gas issuing from said burner to maintain the main flames 48. However, to insure that gas shall not be supplied to said main flames through said valve 23 when the water circulating pump 8 is not operating, and that said valve 23 shall be shut to terminate the operation of said burner 20 if and when the temperature of the water in the system exceeds a predetermined degree, and to insure that said valve shall be shut if and when the pilot flame 47 is accidentally extinguished, and that all of the elements of the apparatus are maintained in proper cooperative relation when they are operated; I provide an electric controlling system cooperatively connecting them and preferably such as shown in Fig. III.

As shown in Fig. III, the heater controlling circuit comprising the conductors 50 and 51 may be energized from any suitable source, preferably the 110 volt supply circuit comprising the conductors 52 and 53. Said circuit connects said pump motor 11, valve motor 25, and fan motor 36 in multiple relation between said conductors 50 and 51, as shown in Fig. III. The adjustable room thermostat 54 may be of any convenient form and includes a switch 55 in said conductor 50. The construction and arrangement thereof are such that said thermostat 54 operates to close said heater circuit, by said switch 55, whenever the temperature of the atmosphere surrounding it falls below the degree for which it is set, and to open said circuit when said temperature rises above that predetermined degree.

In order to break said heater circuit, regardless of the position of the switch 55, if and when the flame 47 is extinguished, I provide the bulb 57 in position to be heated by said flame 47 and connected by the tube 58 with the corrugated metal bellows 59 which carries the safety pilot switch member 60 which normally closes said circuit between the terminals 61 and 62 in said conductor 50 whenever the fluid contents of said bulb 57 and tube 58 are heated to a predetermined degree by said pilot flame 47. However, the arrangement is such that if said flame 47 is extinguished, the fluid in said bulb 57, tube 58, and bellows 59 contracts, and breaks said circuit by movement

of said switch member 60 to the left away from said terminals 61 and 62.

All three motors 11, 25, and 36 are thus controlled, together, both by the room switch 5 55 and by the safety pilot switch 60. However, it is desirable to continue the circulation of water in the system by the pump 8 and to continue to eliminate products of combustion from the chamber 5 by the fan 34 10 when the main gas valve 23 is closed, if such closure is effected because the water in the system has become too hot. Therefore, I arrange the pump motor 11 and fan motor 36 15 in series relation with both of said switches 55 and 60, although said motors are in multiple relation with each other, as shown in Fig. III, but provide another switch 64 to open and close the circuit of said valve motor 25, independently of said motors 11 and 36, 20 in accordance with the temperature of the water in the heater, say at the delivery pipe 18. Said switch 64 is normally closed by the spring 65 but is adapted to be opened 25 against the stress of said spring 65 conveniently by means of the corrugated metal bellows 67 containing a heat expansive fluid and in cooperative relation with said water pipe 18, as indicated in Fig. III. It is to be understood that the stress of said spring 65 30 upon said switch 64 tending to close it, may be varied by adjustment of the screw 68 to thus vary the temperature at which said switch is opened, against the stress of said spring 65, by said expansible device 67.

As indicated in Fig. III, said valve 23 may have its stem 69 provided with the gear rack 70 engaging the gear pinion 71 on the armature shaft 72 of said valve motor 25 so that whenever said heater circuit is closed through said motor 25, the latter turns, counterclockwise in Fig. III, to open said valve 23, against the stress of said spring 26. Whenever said heater circuit is broken through said valve motor 25, at either of said switches 55, 60, 40 or 64, the spring 26 is effective to close said valve 23 and thus permit the heater to be gradually cooled by the continued operation of the water pump motor 11 and flue fan motor 36. Moreover, the gas valve motor 25 45 cannot be operated to open said gas valve 23 to the main burner 20 when the pump motor 11 and fan motor 36 are deenergized by the opening of the circuit at either of the switches 55 or 60. Therefore, the maximum efficiency 50 and safety of the device are secured.

However, it is to be understood that any suitable form of thermostatically controlled gas valve and switches may be employed in lieu of those which I have chosen for illustration. Therefore, I do not desire to limit myself to the precise details of construction or arrangement or method of operation herein set forth, as it is obvious that various modifications may be made therein, without departing from the essential features of my

invention, as defined in the appended claims.

I claim:

1. In an electrical controlling system for a gas water heater, the combination with a main gas burner; an electrically operative and controlled main gas burner valve; an electrically operative and controlled pump for circulating water through said heater; an electric circuit including the pump motor and main gas valve motor, in multiple relation; a thermostatically operative electric switch controlling the branch circuit through said main gas valve motor independently of said other motor, for opening and closing that branch circuit in accordance with the temperature of the water heated; a thermostatically operative electric room switch for opening and closing said multiple circuit in accordance with atmospheric temperature; and means for supplying the entire circuit with current at the same voltage; whereby said multiple circuit is closed and said valve motor and pump motor energized when said room switch is closed, and deenergized when that switch is opened; and said branch circuit through said valve motor is broken, independently of the branch circuit through said pump motor, and the gas valve closed, if and when the temperature of the water heated exceeds a predetermined degree.

2. In an electrical controlling system for a gas water heater, the combination with a main gas burner; of a pilot gas burner in cooperative relation with said main gas burner; an electrically operative and controlled main gas burner valve; an electrically operative and controlled water pump for circulating water through said heater; an electric circuit including the pump motor and main gas valve motor, in multiple relation; a thermostatically operative electric switch controlling the branch circuit through said main gas valve motor independently of said other motor, for opening and closing that branch circuit in accordance with the temperature of the water in said heater; a thermostatically operative electric room switch for opening and closing the multiple circuit through said motors contemporaneously in accordance with atmospheric temperature; a thermostatically operative electric pilot switch, in series with said room switch, for opening and closing said multiple circuit through said motors contemporaneously, in accordance with the temperature at said pilot burner; and means for supplying the entire circuit with current at the same voltage; whereby said multiple circuit is closed and said valve motor and pump motor are energized when said room switch is closed, and deenergized when that switch is opened; and if and when the flame at said pilot burner is extinguished, said multiple circuit is broken at said pilot switch, whether said room switch is closed or not; and said branch circuit

through said valve motor is broken, independently of the branch circuit through said pump motor, and the gas valve closed, if and when the temperature of the water heated exceeds a predetermined degree.

3. In an electrical controlling system for a gas water heater, the combination with a main gas burner; of a pilot gas burner in cooperative relation with said main gas burner;
- 10 an electrically operative and controlled main gas burner valve; an electrically operative and controlled pump for circulating water through said heater; an electrically operative and controlled fan for discharging products
- 15 of combustion from said heater; an electric circuit including the pump motor, fan motor, and main gas valve motor, in multiple relation; a thermostatically operative electric switch controlling the branch circuit through
- 20 said main gas valve motor independently of said other motors, for opening and closing that branch circuit in accordance with the temperature of the water in said heater; a thermostatically operative electric room
- 25 switch for opening and closing the multiple circuit through all of said motors contemporaneously in accordance with atmospheric temperature; a thermostatically operative electric pilot switch, in series with said room
- 30 switch, for opening and closing said multiple circuit through all of said motors contemporaneously, in accordance with the temperature at said pilot burner; and means for supplying the entire circuit with current at
- 35 the same voltage; whereby said multiple circuit is closed and said valve motor, pump motor, and fan motor are energized when said room switch is closed, and deenergized when that switch is opened; and if and when
- 40 the flame at said pilot burner is extinguished, said multiple circuit is broken by said pilot switch, whether said room switch is closed or not; and said branch circuit through said valve motor is broken, independently of the
- 45 branch circuits through said pump motor and fan motor, and the gas valve closed, if and when the temperature of the water heated exceeds a predetermined degree, but said pump and fan then continue to operate to
- 50 reduce the temperature in the heater to a predetermined degree.

In testimony whereof, I have hereunto signed my name at Conshohocken, Pennsylvania, this second day of November, 1931.

55 ROBERT J. DOUGHERTY.
